United States Patent Office

Des. 190,366
Patented May 23, 1961

190,366

TRACTOR

Igor Kam Lukin, Milwaukee, and Nolan Rhoades, Beloit,
Wis., assignors to Simplicity Manufacturing Company,
Port Washington, Wis., a corporation of Wisconsin

Filed June 13, 1960, Ser. No. 60,923

Term of patent 14 years

(Cl. D14—3)

Des. 190,366

PAGE 2

The dominant features of our design reside in those portions thereof illustrated in full lines.

We claim:

The ornamental design for a tractor, as shown and described.
